BY Victor J. Evans

ATTORNEY

G. J. Baker

WITNESS:

UNITED STATES PATENT OFFICE.

JOHN DREISTADT, OF WILKES-BARRE, PENNSYLVANIA.

DESIGN FOR A COMBINATION BOWL AND SPOON HOLDER.

Application filed March 31, 1922. Serial No. 1,469. Term of patent 14 years.

To all whom it may concern:

Be it known that I, JOHN DREISTADT, a citizen of the United States of America, residing at Wilkes-Barre, in the county of Luzerne and State of Pennsylvania, have invented a new, original, and ornamental Design for Combination Bowl and Spoon Holder, of which the following is a specification, reference being had to the accompanying drawings, forming a part hereof.

The figure is a perspective view of a combination bowl and spoon holder showing my new design.

I claim:—

The ornamental design for a combination bowl and spoon holder, as shown.

JOHN DREISTADT.
